MECHANISM FOR DISPENSING POWDERED MATERIALS

William J. Dobkin, Jackson Heights, N. Y., assignor to Mac. B. Feinson, New York, N. Y.

Application August 15, 1941, Serial No. 407,016

9 Claims. (Cl. 222—161)

This invention relates to mechanisms for dispensing powdered materials, as for example, the dispensing of powdered soap or the like. It is an object of this invention to provide a mechanism of the character described which will dispense small quantities of a powder from a powder container which will automatically agitate the powder to keep it in condition to be dispensed.

In the dispensing of powder difficulty is experienced in that, as the powder rests within the container, it tends to settle down and cake, thus interfering with the free flow of the powder into the dispensing apparatus. It is an object of this invention to prevent this phenomena by causing the dispensing operation itself to agitate the powder in a manner to break up the caking tendency and cause the powder to flow freely into the dispensing apparatus.

It is a further object to provide a dispenser of the character described which can be readily attached to a wall and which, when so attached, presents no visible manner in which it can be removed.

It is a further object to provide a dispenser of the character described in which, for manufacture, cleansing and repair purposes, the various elements may be readily assembled and disassembled but which nevertheless, when it is intentionally disassembled, will maintain its parts firmly in their intended places.

It is a further object to provide a mechanism of the character described which will give a warning to the operator when the supply of the powdered material becomes nearly exhausted.

It is a further object to provide a mechanism of the character described which, in its normal position ready for operation, keeps all of the external orifices closed against the intrusion of moisture so that, if the powder to be dispensed be of a character which is more likely to cake because of the presence of moisture, nevertheless such caking is prevented by keeping the material dry.

It is a further object to provide a dispenser of the character described having means within the dispensing apparatus itself for preventing caking of the powdered material as it passes through the container into the dispensing apparatus.

Other objects will in part be obvious and will in part appear hereinafter.

This invention accordingly comprises a machine embodying the features, characteristics and properties and the relationship of the elements which will be exemplified in the machine herein described and the scope of the application of the invention will be indicated in the claims.

For a fuller understanding of the nature and objects of the invention, reference should be had to the following detailed description taken in connection with the accompanying drawings, in which:

Figure 1 is a front elevation of a dispenser embodying this invention.

Figure 2 is a view from a similar position, showing the back supporting plates with the powder container removed.

Figure 3 is a section on the line 3—3 of Figure 1, with the device ready for actuation.

Figure 4 is a view similar to Figure 3, but showing the dispensing element at the end of the actuating stroke.

Figure 5 is a rear view of the powder container.

Figure 6 is a top plan view of the mechanism, certain of the parts being broken away.

Figure 7 is a section on the line 7—7 of Figure 3.

Figure 8 is a side elevation of a modified form of the device.

Figure 9 is an enlarged view, mostly in section, of the operating mechanism.

Figure 10 is a view similar to Figure 9 except that the dispensing element is at the end of the dispensing stroke.

Figure 11 is a detail.

The container 10, carrying at its lower end the dispensing element 11, which is so constructed and arranged that by the movement of the dispensing element the container itself is bodily moved.

In the form of the invention disclosed in Figures 1 to 7, there is provided a wall plate 12 having a portion 13 adapted to rest flat against the wall, and a surrounding flange 14, within which the powder container is carried. This plate 12 may be attached to the wall by screws 15, or any other suitable manner, and at the upper end it is provided with a boss 16 having a female thread to receive a screw 17, for a purpose to be described, at its lower end; and plate 12 is provided with two lugs 18 to receive the lower ends 40 of a plate 20. This plate 20 has an offset portion 21 at its upper end, having an opening 22 for the screw 17 so that the plate 20 may be held in place upon the plate 12 by means of the lugs 18 at the bottom and the screw 17 at the top.

The plate 20 carries at its lower end a circular boss 23 adapted to receive and center a spring 24 and having a slot 25 cut through this boss to receive a latch 26, to be described.

The container 10 comprises the back wall 27 and the front member 28, carrying top and bottom walls 29 and 30 and side walls 31 and 32 which may be welded to the back wall 27 as shown at 33 to form a closed container. The top wall 29 has a filling opening 29a closed by a cover 55 member 34.

Upon the upper end of the plate 20 there is provided a pair of spaced ears 35 fitting between a similar pair of ears 36 upon the back wall 27, and attached to the back edge of the cover 34 there is provided a sleeve 37 adapted to fit between the ears 35. A pin 38 extends through both pairs of

ears and the sleeve 37 to hinge the cover and the container and the plate together. The cover 34 is provided with a lock 39.

The container 10 is provided at its lower end with a pair of aligned openings 40 and 41 in the front and rear walls respectively, and at this point the rear wall is dished inwardly as shown at 42 to provide a space within which certain parts of the operating mechanism may be housed. The cylinder 43 extends through the openings 40 and 41 and is provided with a shoulder 44 adapted to bear against the front face of the container at the opening 40. The rear end of this cylinder 43 is provided with oppositely disposed slots 46 adapted to engage lugs 47 extending inwardly into the opening 41 to prevent rotation of the cylinder. Within the cylinder there is slidably mounted a piston 48 having a shoulder 49 forming the termination of a reduced extension 50 of the piston. This reduced extension is bifurcated at its outer end as shown at 51 to receive the latch 26, which is pivoted to it.

The cylinder 43 has its inner end threaded both inside and out and upon its exterior is threaded a nut 53, adapted to bear against the face of the opening 41 to hold the cylinder in place, and screwed upon the interior end of the cylinder is a second nut 54, having a flange 55 adapted to bear against the end of the cylinder and against the edge of the nut 53 to lock the latter in place. The forward end of the nut 54 is positioned to engage the shoulder 49 and limit the movement of the piston within the cylinder. The other side 56 of the nut 54 beyond the flange 55 has a cylindrical surface to serve to center the spring 24.

With this construction as assembled, the piston 48 is attached to the boss 23 by the latch 26, whereas the cylinder 43 is fixed upon the container. Thus the spring 24 pressing against the plate 20 and against the flange 55, presses the lower end of the container 10 upwardly until the shoulder 49 engages the face of the nut 54 to restrain further movement. To cushion the contact between this shoulder and the nut there is preferably provided a dished spring washer 57, between the shoulder 49 and the nut 54.

The upper face of the cylinder 43 within the container 10 is cut away as shown at 58 at a point such that it will be in registry with a cut away portion 59, in the piston, when the dispenser is ready for actuation. As shown, this cut away portion 59, see Figure 11, extends on both sides of the median line, the outer end of the piston being connected with the inner end by a knife edged portion 60.

The cylinder 43, exterior to the container 10, is provided preferably with a pair of openings 61, one on each side of the median line, in position to be in registry with the cut away portion 59 of the piston, when the dispensing mechanism is in the actuated position of Figure 4. It will thus be seen that in the position shown in Figure 3, the powdered material will fall into the recess 59, through the cut away portion 58, and will be thrown to one side or the other by the knife edge portion 60, this action tending to break up any caking of the material. Since, therefore, as the cylinder is pressed inwardly to bring the cut away portion 59 into registry with the openings 61, the powdered material contained within the recess 59 is discharged through the openings 61, and when thereafter the pressure upon the cylinder 43 is relieved, the spring 26 will force the container 10 about its pivot 38, returning the parts to the position shown in Figure 3, and again

withdrawing the piston within the cylinder ready to receive another charge of the powdered material.

Within the container 10 there is a pivoted rod 65 upon the pivot 66 in the position to engage a gong 67, being positioned to swing freely. This rod 65, however, extends downwardly within the powdered material 68 within the container and cannot swing freely so long as there is any substantial quantity of the powdered material within the container. As soon, however, as the quantity of the powdered material has fallen below the lower end of the rod, the rod is caused to swing at every operation of the dispenser, causing it to strike the gong. This construction causes the rod to function as a warning signal when the supply of the powdered material runs low.

This device may be assembled upon the wall, as follows:

First. The wall plate 12 may be attached to the wall by the screws 15. Thereafter the lower edge of the plate 20 may be inserted behind the lugs 18. Then by mechanically compressing the spring 24 the latch 26 may be caught inside the boss 23 and the spring 24 released, the latch 26 being thereafter held in place by the spring 24 and its engagement with the boss 23. The upper end of the plate 20, and hence of the depressing mechanism, is secured in place by a screw 17 and 30 screwed into the boss 16.

The dispenser is now in position to be operated, the container 10 being held forward by the spring 26. On pushing in the cylinder 43 which is provided with a pusher 43a for that purpose, the 35 whole container is moved about its pivot, causing the sliding action of the piston and the discharge of the powdered material, as previously described.

The form of the invention described in Figures 8, 9 and 10 embodies a cylindrical stud 100 supported by and extending downwardly from the wall 101, and on this side there is slidably mounted a cylinder 102 which carries a screw 103 moveable in a slot 104 upon the stud 100 to limit the sliding motion of the cylinder and preventing any rotating motion thereof. A small spring 105 may be attached upon the stud 100 by a screw 106 in position to engage the screw 103 at the end of its travel to cushion the outwardward movement of the cylinder.

The cylinder 102 carries a threaded cup 107 into which may be screwed a glass container 108, adapted to receive the powdered material to be dispensed and carrying on its upper end a cover 109 through which it may be filled. A washer 110 may be inserted to secure a moisture tight joint between the container 108 and the cup 107.

The cylinder 102 at a point in registry with the interior of the glass container is cut away as shown at 111, and at a point in registry with this cut away portion 111, when the device is in a position of rest the stud 100 is provided with a cut away portion 112, which may be similar to the cut away portion 59 of the previous embodiment. The two parts of the stud, on opposite sides of the cut away portion being connected by the knife edge portion 113, as previously described. The outer end 114 of the stud 100 is provided with a recess 115 to receive one end of a spring 116, the other end of which 117, is carried within a hollow stud member 118, which closes the outer end of the cylinder. The dished washer 119 may be inserted within the cylinder in position to cushion the contact between the hollow stud 118 and the end 114 of

the stud 100. When the stud 118 is pushed inwardly at its maximum movement at the close of the depressing stroke, the cylinder 102 is provided with an opening 120 on each side of the median line to receive the discharge from the cut away portion 112, when the stud 118 is depressed.

By the foregoing constructions it would be clear that the powder container is itself mounted to be moved with the depressing element every time the latter is pushed in to cause the depressing operation. Thus the material within the container is consistently shaken up and the tendency to cake is overcome.

Since certain changes may be made in the above construction and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which as a matter of language might be said to fall therebetween.

Having described my invention, what I claim as new and desire to secure by Letters Patent is:

1. A device of the character described comprising in combination a container for powder, means for supporting said container to permit a forward and backward movement thereof, a dispensing mechanism associated with said container to dispense powder during said movement, and having signal mechanism within said container below the normal powder level therein, restrained from operation by the powder, but constructed and arranged to sound a signal in response to each movement whenever the powder level falls below said signal mechanism.

2. A device of the character described comprising in combination a container for powder, means for supporting said container to permit a forward and backward movement thereof, a dispensing mechanism associated with said container to dispense powder during said movement, and having a mechanism within said container normally free to sound a signal, but held below the normal level of the powder within said container, and constructed and arranged to be withheld from sounding by the presence of said powder.

3. A device of the character described comprising in combination a container for powder, means for supporting said container to permit a forward and backward movement thereof, a dispensing mechanism associated with said container to dispense powder during said movement, and having an element within the container depending below the normal powder level within said container in a position to strike the said wall of the container in response to the said movement whenever the powder within said container falls below a predetermined level.

4. A device of the character described, comprising a support, a horizontally disposed piston member carried by said support, a cylinder moveable on said piston, a powder container pivoted to said support above said cylinder and mounted on said cylinder, said cylinder and piston having cooperating openings constructed and arranged in one relative position to receive pow-

der into the recess in said piston, and in another position to discharge said powder to the exterior of said cylinder, spring means for holding the parts in the last mentioned relative position.

5. A device in accordance with claim 4 in which the recess in said piston is constructed and arranged to divide the powder falling into it from said container to prevent caking thereof.
- 10 6. A device of the character described comprising a container for powder and support therefor, means for hinging the upper edge of said container to said support, a dispensing mechanism at the lower end of said support having a pair of cooperating elements with all said elements being mounted on said container, and one of said elements being connected to said support whereby movement of said container about said hinge causes the relative movement of said members, spring means for urging the lower edge of said container away from said support, said members having cooperating recesses constructed and arranged in one relative position thereof to receive powder from said container and in the other relative position to discharge said powder to the exterior.
- 15 7. A device of the character described comprising a container for powder and support therefor, means for hinging the upper edge of said container to said support, a dispensing mechanism at the lower end of said support having a pair of cooperating elements comprising a cylinder attached to said container, and a piston moving within said cylinder and connected to said support, cooperating recesses in said piston and cylinder constructed and arranged to receive powder into the recess in said piston in one relative position of said members and to discharge the said powder to the exterior.
- 20 8. A device of the character described, comprising a wall plate adapted for permanent attachment to a wall, having lugs at the bottom thereof, a container having a back plate hinged thereto constructed and arranged to fit under said lugs and to be attached to the upper end of said wall plate by a screw, and spring means for holding the lower end of said container spaced from said wall plate, a dispensing mechanism carried by the lower end of said container, constructed and arranged to be operated by the movement of said container about its hinge.
- 25 9. A device of the character described comprising a support, a container for powdered soap, means for supporting said container from said support for horizontal movement relative to said support, a pair of dispensing elements disposed below said container-supporting means and having cooperating openings constructed and arranged in relative positions, and horizontally movable relative to each other from one position to the other to effect the dispensing operation, in one position to receive powder from said container and in another position to discharge the powder so received, one of said members being attached to said support and the other being connected to said container whereby the relative movement of said dispensing members creates a horizontal agitation of said container.
- 30 10. A device of the character described comprising a support, a container for powdered soap, means for supporting said container from said support for horizontal movement relative to said support, a pair of dispensing elements disposed below said container-supporting means and having cooperating openings constructed and arranged in relative positions, and horizontally movable relative to each other from one position to the other to effect the dispensing operation, in one position to receive powder from said container and in another position to discharge the powder so received, one of said members being attached to said support and the other being connected to said container whereby the relative movement of said dispensing members creates a horizontal agitation of said container.
- 35 11. A device of the character described comprising a support, a container for powdered soap, means for supporting said container from said support for horizontal movement relative to said support, a pair of dispensing elements disposed below said container-supporting means and having cooperating openings constructed and arranged in relative positions, and horizontally movable relative to each other from one position to the other to effect the dispensing operation, in one position to receive powder from said container and in another position to discharge the powder so received, one of said members being attached to said support and the other being connected to said container whereby the relative movement of said dispensing members creates a horizontal agitation of said container.
- 40 12. A device of the character described comprising a support, a container for powdered soap, means for supporting said container from said support for horizontal movement relative to said support, a pair of dispensing elements disposed below said container-supporting means and having cooperating openings constructed and arranged in relative positions, and horizontally movable relative to each other from one position to the other to effect the dispensing operation, in one position to receive powder from said container and in another position to discharge the powder so received, one of said members being attached to said support and the other being connected to said container whereby the relative movement of said dispensing members creates a horizontal agitation of said container.
- 45 13. A device of the character described comprising a support, a container for powdered soap, means for supporting said container from said support for horizontal movement relative to said support, a pair of dispensing elements disposed below said container-supporting means and having cooperating openings constructed and arranged in relative positions, and horizontally movable relative to each other from one position to the other to effect the dispensing operation, in one position to receive powder from said container and in another position to discharge the powder so received, one of said members being attached to said support and the other being connected to said container whereby the relative movement of said dispensing members creates a horizontal agitation of said container.
- 50 14. A device of the character described comprising a support, a container for powdered soap, means for supporting said container from said support for horizontal movement relative to said support, a pair of dispensing elements disposed below said container-supporting means and having cooperating openings constructed and arranged in relative positions, and horizontally movable relative to each other from one position to the other to effect the dispensing operation, in one position to receive powder from said container and in another position to discharge the powder so received, one of said members being attached to said support and the other being connected to said container whereby the relative movement of said dispensing members creates a horizontal agitation of said container.
- 55 15. A device of the character described comprising a support, a container for powdered soap, means for supporting said container from said support for horizontal movement relative to said support, a pair of dispensing elements disposed below said container-supporting means and having cooperating openings constructed and arranged in relative positions, and horizontally movable relative to each other from one position to the other to effect the dispensing operation, in one position to receive powder from said container and in another position to discharge the powder so received, one of said members being attached to said support and the other being connected to said container whereby the relative movement of said dispensing members creates a horizontal agitation of said container.
- 60 16. A device of the character described comprising a support, a container for powdered soap, means for supporting said container from said support for horizontal movement relative to said support, a pair of dispensing elements disposed below said container-supporting means and having cooperating openings constructed and arranged in relative positions, and horizontally movable relative to each other from one position to the other to effect the dispensing operation, in one position to receive powder from said container and in another position to discharge the powder so received, one of said members being attached to said support and the other being connected to said container whereby the relative movement of said dispensing members creates a horizontal agitation of said container.
- 65 17. A device of the character described comprising a support, a container for powdered soap, means for supporting said container from said support for horizontal movement relative to said support, a pair of dispensing elements disposed below said container-supporting means and having cooperating openings constructed and arranged in relative positions, and horizontally movable relative to each other from one position to the other to effect the dispensing operation, in one position to receive powder from said container and in another position to discharge the powder so received, one of said members being attached to said support and the other being connected to said container whereby the relative movement of said dispensing members creates a horizontal agitation of said container.
- 70 18. A device of the character described comprising a support, a container for powdered soap, means for supporting said container from said support for horizontal movement relative to said support, a pair of dispensing elements disposed below said container-supporting means and having cooperating openings constructed and arranged in relative positions, and horizontally movable relative to each other from one position to the other to effect the dispensing operation, in one position to receive powder from said container and in another position to discharge the powder so received, one of said members being attached to said support and the other being connected to said container whereby the relative movement of said dispensing members creates a horizontal agitation of said container.
